UNITED STATES PATENT OFFICE

157,361

TRUCK BODY

Wade O. Ford, San Angelo, Tex.

Application March 15, 1948, Serial No. 145,101

Term of patent 14 years

(Cl. D14—3)

To all whom it may concern:

Be it known that I, Wade O. Ford, a citizen of the United States, residing at San Angelo, in the county of Tom Green and State of Texas, have invented a new, original, and ornamental Design for Truck Body, of which the following is a specification, reference being had to the accompanying drawing, forming part thereof.

In the drawing:

The dotted line showing in the drawing figures is for illustrative purposes only.

I claim:

The ornamental design for a truck body, as shown and described.

WADE O. FORD.
